HAIR DRYER ATTACHMENT

Arthur M. Felske, Westport, Conn., assignor to General Electric Company, a corporation of New York

Filed Sept. 19, 1963, Ser. No. 76,637

Term of patent 14 years

(Cl. D86—10)

FIG. 1

FIG. 2

FIG. 3

FIG. 4

FIG. 1 is a perspective view of a hair dryer attachment showing my new design;

FIG. 2 is a side elevational view of the attachment of FIG. 1;

FIG. 3 is an end elevational view thereof as seen from the left of FIG. 2; and

FIG. 4 is an end elevational view thereof as seen from the right of FIG. 2.

I claim:

The ornamental design for a hair dryer attachment, substantially as shown.
